UNITED STATES PATENT OFFICE.

LINCOLN H. CLEMENTS, OF CLEMENTS, MINNESOTA

GOVERNOR FOR INTERNAL-COMBUSTION ENGINES

Application filed August 24, 1925. Serial No. 51,992.

To all whom it may concern:

Be it known that I, LINCOLN H. CLEMENTS, a citizen of the United States, residing at Clements, in the county of Redwood and State of Minnesota, have invented certain new and useful Improvements in Governors for Internal-Combustion Engines, of which the following is a specification.

This invention relates to governors for internal combustion engines and the primary object is to provide an efficient and practical governor which is particularly adapted for use in connection with an internal combustion engine which has been removed from a motor vehicle and is subsequently used for stationary power purposes. Further and more specific objects will be disclosed in the course of the following specification, reference being had to the accompanying drawings, wherein:

Figure 1 is a side elevation of a Ford engine, removed from its chassis, and showing the application of my improved governor thereto.

Figure 2 is a plan view of the governor and a part of the engine as on the line 2-2 in Figure 1.

Figure 3 is a sectional elevation as on the line 3-3 in Fig. 2.

Referring to the drawings more particularly and by reference characters A designates the block or body of an internal combustion engine having a crank case B, secured by bolts C, an intake manifold D, a carburetor E, having the usual butterfly valve F, and a fan G having a shaft H provided with a pulley J (driven by a belt, not shown), all of common and well known construction.

Secured upon the engine, preferably by two of the bolts C, is a standard 4, having a tubular upper portion 5, in the ends of which are arranged a pair of bearings or bushings 6. An elongated sleeve or hollow rod 7 is rotatably arranged in the bushings 6 and is prevented from moving longitudinally by a pair of collars 8 and 9 having respective set screws 10 and 11. Integral with the collar 9 is a pulley 12 adapted to be driven by a belt 13 secured upon the fan shaft H.

Slidably secured within and extending rearwardly from the sleeve 7 is a rod 14 having a rigidly secured head piece 15. A pair of centrally actuated weights or balls 16

are connected by links 17 and 18, respectively, to the head member 15 and to ears 19 projecting from the collar 8 on the sleeve 7. The spindle or rod 14 is held in a yieldingly extended position, against the movement of the balls 16, by a spring 20, within the sleeve 7, and the tension of the spring may be adjusted, by a set screw 21, which is threaded into a goose neck 4*, of the standard 4, and may be locked by a suitable lock nut 22. As the set screw 21 operates in a stationary member 4* it is obvious, and considered as an important feature of this invention, that the regulating or adjusting of the governor may be accomplished while it is in motion and when the engine is running. The spindle 7 is preferably lubricated by means of an oil or grease cup 23, secured upon the standard as shown.

The head member 15 is provided in its rear end with a tapered recess 23, in which engages the pointed end of a rod 24. The rear end of this rod is pivotally secured to the crank arm 25 of a butterfly valve 26 in a manifold D. The rod 24 is held against vibration and in constant engagement in the recess 23 by a spring 27 which acts against the crank arm 25.

In operating the engine its speed is first adjusted, when running idle, by manipulating the valve F, in the usual manner. Or its normal or desired speed may be manually changed by adjusting this valve even after the motor is put to work. The object of the governor, however, is to so control the valve 26 that the adjusted speed of the motor will be automatically maintained regardless of the stress or resistance to which the engine is subjected. Thus, when the engine is, for any reason, slowed up the weights 16 will close in, spreading the head 15 away from the sleeve 7 and thus actuating the member 24 in a direction which will open the valve 26 and thus permit a greater volume of gas to be introduced into the combustion cylinders, with the result of increased acceleration of the engine's speed. And, when, for instance the motor is relieved from working duty, and has a tendency to speed, then the centrifugal action of the weights 16 will effect a closing of the valve 26 to reduce the volume of gas and thus slow up the motor.

To reduce or increase the normal working speed or power of the engine, when the same is running, it is only necessary to release

the nut 22 so that the set screw 21 may be regulated to adjust the tension of the spring 20.

It is understood that various modifications may be made in the general design and structural details of the invention as herein illustrated and described, providing, however, that such modifications come within the spirit and scope of the appended claims.

Having now therefore, fully shown and described my invention, what I claim to be new and desire to protect by Letters Patent is:—

1. A governor for internal combustion engines, comprising a standard secured to the engine on one side thereof, and having a goose neck extension forming a U-shaped opening in its forward end, a sleeve rotatably secured in the standard and extending with its fore end into said opening, means on said fore end of the sleeve for rotating the same, a weight actuated rod in the sleeve and associated with a gas valve in the engine, a spring in the sleeve for resisting the

forward motion of the rod, and a set screw threaded in said goose neck extension and extending into the sleeve for adjusting said spring.

2. A governor for internal combustion engines, comprising a standard secured to the engine on one side thereof, and having a goose neck extension forming a U-shaped opening in its forward end, a sleeve rotatably secured in the standard and extending with its fore end into said opening, means on said fore end of the sleeve for rotating the same, a weight actuated rod in the sleeve and associated with a gas valve in the engine, a spring in the sleeve for resisting the forward motion of the rod, and a set screw threaded in said goose neck extension and extending into the sleeve for adjusting said spring, said set screw having a lock nut, which, when released, will permit the set screw to be adjusted when the governor is in motion.

In testimony whereof I affix my signature.

LINCOLN H. CLEMENTS.
